United States Patent Office

Des. 186,436
Patented Oct. 27, 1959

186,436

PHOTOGRAPHIC CAMERA

Clare E. Hodgman, Mamaroneck, N.Y., assignor to General Aniline & Film Corporation, New York, N.Y., a corporation of Delaware

Application December 22, 1958, Serial No. 53,854

Term of patent 14 years

(Cl. D26—1)

FIG. 1

FIG. 3

Fig. 1 is a perspective view of the front and one side of a photographic camera showing my new design the opposite side being substantially a mirror image thereof;

Fig. 2 is a rear elevational view thereof; and

Fig. 3 is a front elevational view.

I claim:

The ornamental design for a photographic camera, substantially as shown and described.
